United States Patent Office

Des. 205,081
Patented June 21, 1966

205,081

DESK LAMP

Morison S. Cousins, Bayside, N.Y., assignor to Tensor Corporation, Brooklyn, N.Y., a corporation of New York

Filed Mar. 11, 1965, Ser. No. 84,206

Term of patent 14 years

(Cl. D48—20)

FIG. 5.

FIG. 6.

FIG. 7.

FIG. 8.

FIG. 1 is a perspective view of a desk lamp showing my new design;

FIG. 2 is a front elevational view thereof;

FIG. 3 is an elevational view of the right side of same with respect to FIG. 2, and as seen from the other figures, the opposite side is a mirror image thereof;

FIG. 4 is a rear side view with respect to FIG. 2;

FIG. 5 is a top plan view thereof looking down on to the reflector top of the lamp;

FIG. 6 is a bottom plan view thereof looking up into the lamp;

FIG. 7 is a view taken along line 7—7 of FIG. 2; and

FIG. 8 is a fragmentary and partially sectional view showing the relationship of the lamp reflector, lamp bulb and its socket housing, and the tie structure for supporting the reflector in parasol relationship over said bulb.

I claim:

The ornamental design for a desk lamp, as shown and described.
